US00D420538S

United States Patent [19]**Arko et al.****Patent Number: Des. 420,538****Date of Patent: ** Feb. 15, 2000**[54] **CHAIR**

[75] Inventors: **Robert P. Arko**, Palo Alto; **Steven R. Takayama**, Atherton, both of Calif.; **Eric T. McClure**; **Kenneth J. Penning**, both of Grand Rapids, Mich.; **Steven J. Dessaint**, Belmont, Mich.

[73] Assignee: **Steelcase Inc.**, Grand Rapids, Mich.

[**] Term: **14 Years**

[21] Appl. No.: **29/087,013**

[22] Filed: **Apr. 24, 1998**

[51] **LOC (7) Cl. 06-06**

[52] **U.S. Cl. D6/500; D6/366**

[58] **Field of Search D6/334, 364, 365, D6/366, 367, 500, 501, 502; 297/411.2, 445.1, 446.1, 448.1**
